(57) **CLAIM**

The ornamental design for a basketball system pole, substantially as shown and described.

DESCRIPTION

FIG. 1 is a top front perspective view of a basketball system pole in accordance with the present invention.

FIG. 2 is a top rear perspective view thereof.

FIG. 3 is a side elevation view thereof.

FIG. 4 is an alternate side elevation view thereof.

FIG. 5 is a front elevation view thereof.

FIG. 6 is a rear elevation view thereof; and,

FIG. 7 is a top plan view thereof.

The broken lines illustrate environmental subject matter and form no part of the claimed design.

1 Claim, 7 Drawing Sheets
